UNITED STATES PATENT OFFICE.

HARRY W. LELAND, OF SOUTH FRAMINGHAM, ASSIGNOR TO HIMSELF AND
JOEL C. CLARK, OF FRAMINGHAM, MASSACHUSETTS.

PLUG FOR ELECTRICAL SWITCH-BOARDS.

SPECIFICATION forming part of Letters Patent No. 258,931, dated June 6, 1882.

Application filed January 3, 1882. (No model.)

To all whom it may concern:

Be it known that I, HARRY W. LELAND, of South Framingham, in the county of Middlesex and State of Massachusetts, have invented 5 certain Improvements in Plugs for Switch-Boards, of which the following is a specification.

This invention relates to electrical connecting or looping-in plugs employed in telephonic exchanges and central offices to loop in or connect the operator's telephone for the purpose of listening to or answering a call from a subscriber, or to ascertain if conversation has ceased, or for any other purpose when the operator desires to connect his telephone with the 15 circuit of one or more subscribers.

The invention has for its object to provide a plug whereby the above-mentioned operations may be performed, and also whereby when the 20 plug is inserted into the circuit of one or more subscribers for listening or talking purposes the telephone and other looped-in or connected apparatus may be cut out from said circuit and electric currents sent to line for signaling purposes.

To this end my invention consists in the provision upon a plug of the ordinary construction of one or more spring-keys, back contacts, and anvils or terminals adapted to connect 25 one or both of the metallic plates of the plug either with the operator's telephone or with current-sending apparatus, one of said connections being automatically effected by the pressure of the spring-key and the other by pressure on said key of the operator's hand holding the plug, as I will now proceed to describe.

Of the accompanying drawings, forming a part of this specification, Figures 1^a and 1^b represent respectively a longitudinal section and 30 plan view of a plug embodying my invention. Figs. 2 and 3 represent diagrams showing the connections therewith.

In carrying out my invention I construct a plug, as usual, of a piece of insulating material, 35 B, having upon its opposite sides plates a b of conducting metal, connected to which are wires leading to the telephone and other apparatus connected or looped into circuit. In my improvement one or both of said plates are formed

in two lengths, one of which is a spring-key, c, 50 resting normally against a back contact, d, said back contact being connected to a wire leading to the telephone. In case the plug is inserted between two subscribers, and it is desired to send electric currents to only one, the 55 opposite conducting-plate is connected directly by means of a wire to the opposite side of the telephone. So normally the looped-in circuit will be through one plate, its key and back contact, through the telephone back through the other connecting-plate; but when the operator desires to signal the subscriber and presses the key upon its anvil the circuit will be from ground through current-generating apparatus, galvanic or magneto, through said key 60 to subscriber's line, as shown in Fig. 2. By releasing the key the circuit is immediately restored through the telephone and other apparatus.

When the operator desires for any reason 70 to send a signaling-current to two subscribers a plug such as shown in Fig. 3 is used, in which two of the above-described keys are used, one on each side of the plug. The normal circuits in this case will be through the back contacts 75 of the keys, and when both keys are pressed down onto their anvils the telephone is cut out and the generating apparatus looped in.

Referring more specifically to the drawings, B represents the insulating material or body 80 of the plug—such as hard rubber formed into the required shape.

a is a plate, of brass or other conducting material, secured to the body B.

b is a plate of brass, also secured to the body 85 B at that end of the plug which is formed for insertion into the subscriber's circuit. The opposite end of the plate b terminates in a spring-key, c, which normally rests against a back contact, d.

c' is an anvil or terminal on the body B, arranged so that the free end of the key c can come in contact with it when the key is displaced or pressed inwardly. The anvil or terminal c' is connected by a wire, e, with a magneto-generator, M G, or with a battery. The back contact, d, is connected by a wire, g, with a transmitter, T, and the operator's telephone,

and the under plate, *a*, is connected by a wire, *f*, with the operator's telephone and transmitter.

Fig. 2 shows the above-described key arranged in a circuit with two subscribers, the normal circuit being from subscriber No. 1 through plate *b*, key *c*, and back contact, *d*, transmitter and receiver *a* to subscriber 2. The same figure shows the connection from anvil *c'* of the plug through a magneto-generator, *M*, *G*, to the ground. By pressing the key upon its anvil the transmitter and receiver are disconnected and a circuit formed to ground, whereby magneto signaling-currents can be sent to line. It will be understood that by reversing the plug electric currents can be sent to the other subscriber.

When signals are to be sent to both subscribers the form of plug shown in circuit in Fig. 3 is used. In this form the plate *a* has a spring-key, *c*, and a back contact, *d*, which is insulated from the back contact of the other key. The circuit is normally through the plates *a* *b* and back contacts, *d*, to telephone, and when signal-currents are to be sent both keys are depressed upon their anvils, thus looping in an electric generating apparatus and sending currents to both subscribers, or to either part of the line-circuit in which the plug is inserted. The key *c* virtually takes the place of the independent key usually employed to connect the plug either with the listening-telephone or with the current-sending apparatus, said key being at a distance from the plug, so that it cannot be operated by the hand that holds the plug. It is obvious that by locating a key per-

forming the same function directly on the plug the key can be much more conveniently operated.

I claim—

1. A switch-board plug of the class described, supporting a back contact, a terminal or anvil, and a spring-key, said parts being connected respectively with the operator's telephone, with a generator or battery, and with one of the metal plates of the plug, whereby the operator is enabled to manipulate the key and make and break the usual connections with the same hand that holds the plug, as set forth. 40

2. A switch-board plug of the class described, supporting one or more back contacts, one or more terminals or anvils and one or more spring-keys, said parts being connected respectively with the operator's telephone, a battery or generator, and one or both of the metal plates of the plug, whereby the operator is enabled to make and break the usual connections with the same hand that holds the plug, and when two back contacts, spring-keys, and terminals are provided the operator is enabled to connect both of the metal plates of the plug with a generator or battery, and thereby send currents to both parts of a line-circuit into which the plug is inserted, as set forth. 50

In testimony whereof I have signed my name to this specification, in the presence of two subscribing witnesses, this 20th day of December, A. D. 1881.

HARRY WALTER LELAND.
